Primary Examiner — Cynthia Ramirez(74) *Attorney, Agent, or Firm* — Buchanan Ingersoll & Rooney PC**CLAIM**

The ornamental design for a multi-functional folding cart, as shown and described.

DESCRIPTION

FIG. 1 is a front elevational view of a multi-functional folding cart showing my new design;

FIG. 2 is a rear elevational view thereof;

FIG. 3 is a left side elevational view thereof, the right side being a mirror image;

FIG. 4 is a top plan view thereof;

FIG. 5 is a bottom plan view thereof; and,

FIG. 6 is a perspective view thereof.

The broken lines shown in FIG. 5 are boundaries that form not part of the claimed design.
